(57) **CLAIM**

The ornamental design of a head lamp for a car, as shown and described.

DESCRIPTION

FIG. 1 is a perspective view of the head lamp for a car of the present design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The design can be embodied with metal, glass and plastics. This head lamp is arranged at the front-left and front-right sides of a car. The front side of this head lamp is made of transparent body. This design is characterized in the shape and configuration of the head lamp for a car.
